CLAIM

The ornamental design for a display panel with a computer-generated icon as shown and described.

DESCRIPTION

The file of this patent contains at least one drawing executed in color. Copies of this patent with color drawings will be provided by the Office upon request and payment of the necessary fee.

FIG. 1 is a front view of a display panel or portion thereof with a computer-generated icon according to the claimed design;

FIG. 2 is a top-right perspective view of the computer-generated icon of FIG. 1, shown with the electronic device for completeness of illustration; and,

FIG. 3 is a front view of the computer-generated icon of FIG. 1, shown with an alternative view of the electronic device for completeness of illustration.

The broken line in FIG. 1 illustrates a portion of the display panel, and the broken lines in FIGS. 2 and 3 illustrate the electronic device. None of the broken lines form part of the claimed design.
